UNITED STATES PATENT OFFICE.

WILLIAM F. McCLELLAN, OF SEATTLE, WASHINGTON.

APPARATUS FOR PULVERIZING.

SPECIFICATION forming part of Letters Patent No. 691,163, dated January 14, 1902.

Application filed April 1, 1901. Serial No. 53,871. (No model.)

To all whom it may concern:

Be it known that I, WILLIAM F. McCLELLAN, a citizen of the United States, residing at Seattle, in the county of King and State 5 of Washington, have invented certain new and useful Improvements in Apparatus for Pulverizing; and I do hereby declare the following to be a full, clear, and exact description of the invention, such as will enable others skilled in the art to which it appertains to 10 make and use the same.

My invention relates to improvements in pulverizers, and more particularly to that 15 class of such devices in which opposing currents of air, steam, water, or other gas or fluid are utilized for accomplishing the desired result by concussion.

It consists of means for feeding material to 20 oppositely-disposed jets of gas or liquid and means for rotating said material in opposite directions as the same is brought together by said jets.

It also consists of certain other novel constructions, combinations, and arrangements 25 of parts, as will be hereinafter more fully described and claimed.

In the accompanying drawings, Figure 1 represents a view in front elevation of a pulverizer embodying the features of my invention. Fig. 2 represents a view in side elevation of the same. Fig. 3 represents a longitudinal horizontal sectional view of the same on line *xx* of Fig. 1. Fig. 4 represents a horizontal longitudinal enlarged view of one of 35 the nozzles, and Fig. 5 represents in front elevation a detail view of the rifled tip of one of the nozzles.

Referring to the drawings by numerals, 1 indicates any preferred form of hopper for 40 containing the material to be pulverized, and any desired form of conduits, as 2 2, are provided for conducting the material from said hopper to the position of operation at their lower ends, as at 3 3. I contemplate the use 45 of a plurality of hoppers 1, but may vary the number as desired.

Extending at right angles to the end 3 of each of the ducts 2 is provided a nozzle, as 4, extending into a suitable hood, as 5, and provided at its inner end with a rifled tip, as 6, which tip may be secured in position by

means of a threaded screw, as 7, or in any other suitable manner. The arrangement of each of the nozzles 4 is such that its discharge-opening is directly opposite that of a 55 similar nozzle upon the other side of hood 5.

The bottom of hood 5 is preferably formed with a portion slanting upwardly from each of nozzles 4 toward the center of the hood, as at 8, and then downwardly, as at 9, and the 60 center thereof is adapted to be pierced by a suction-pipe, as 10, which pipe is made in two parts, one extending from below as far upward into the said hood 5 as may be desired, as at 11, and the other part, directly above 65 the first part and spaced therefrom, extends out through the top of hood 5 and to any suitable receiving-chamber for the pulverized material carried by the draft therein.

The slanting portions 9 of the bottom of 70 hood 5 are formed in such manner as to lead to conduits, as 12 12, upon opposite sides of said hood, and said conduits preferably empty into hoppers, as 13 13, provided with comparatively short ducts, as 14 14, leading to 75 oppositely-disposed nozzles, as 15, which are exact duplicates of nozzles 4.

A supply-pipe, as 16, is preferably provided upon either side of hood 5, and is adapted, by means of branch pipes, as 17 17, leading to 80 the various nozzles employed, to supply steam or other suitable pressure thereto, preferably through centrally-arranged nozzles, as 18, within nozzles 4 and 15.

I find that the tips 6 become worn by constant use and must be replaced occasionally, and in order to accomplish this I have provided apertures at suitable points in hood 5 and in the lower end of suction-pipe 10, adapted to be filled by threaded caps, as 19, whereby the hand may be passed into the interior of the apparatus for removing and replacing said tips. The provision of tip 6 with its rifled interior wall is an important feature of the present invention, and it will be seen that 95 either right or left hand rifling may be used; but all of the tips in one device must be provided with rifling running in the same direction, and the said tips being arranged opposite each other will give the material passed therethrough a whirling movement revolving in opposite directions.

Near the bottom of suction-pipe 10 is preferably provided any suitable form of waste-pipe, as 20.

In the operation of my improved pulverizer 5 the material to be pulverized is placed within hopper or hoppers 1 and fed down ducts 2 into the body of the nozzles 4, where it is brought under the influence of steam or other pressure from nozzle 18 and driven through 10 the rifled tips 6, whereby a rotary motion is imparted to the same, and the said nozzles 4 being directly opposite each other will direct the two streams of material revolving in opposite directions against each other, and 15 thereby pulverize the said material. The pulverized portions of material then follow the current of pressure as it escapes through pipe 10 and are adapted to be caught in any suitable receptacle intermediate the length 20 of said pipe 10. Any particles of the material not pulverized are drawn by the action of the escaping pressure over the upward slant 8 of the bottom of hood 5, and the said particles then drop by weight down slant 9, 25 through ducts 12, hoppers 13, and ducts 14, into nozzles 15, where it undergoes another operation exactly similar to that just described, and the pulverized material is drawn up pipe 10, and whatever material may yet 30 remain not pulverized may escape through waste-pipe 20 and may, if desired, be returned to hopper 1.

It will be readily seen by those skilled in the art that a more powerful grinding and 35 pulverizing action is obtained by the means for contacting two streams of oppositely-revolving material than can be otherwise obtained, and this is one of the most important features of my invention.

40 Although I have described in detail one specific embodiment of my invention, yet I do not wish it understood that I mean to limit myself to the exact construction specified, but shall feel at liberty to deviate from the size, shape, and minor details of the present device within the spirit and scope of my invention.

Having thus fully described my invention, what I claim as new, and desire to secure by 45 Letters Patent, is—

1. A pulverizer, comprising in its construction means for supplying material to be pulverized, oppositely-disposed, similarly-rifled nozzles to which said material is supplied, 55 and means for forcing said material through said nozzles, whereby the stream of material from one nozzle is revolved in an opposite direction to the revolutions of the stream of material from the opposite nozzle, substantially as described.

2. A pulverizer, comprising in its construction a suitable hood, hoppers above said hood for supplying material to be pulverized, oppositely-disposed, similarly-rifled nozzles extending into said hood, ducts leading from 60 said supply-hoppers to said nozzles, means for supplying fluid-pressure to said nozzles,

whereby the material from said hopper will be forced in a whirling stream from each of said nozzles and the said streams from the 70 two opposing nozzles caused to contact centrally of the intermediate space, and means for conducting said pulverized material from said hood, substantially as described.

3. A pulverizer, comprising in its construction a hood, a draft-duct leading therefrom and formed of two parts, one extending from beneath said hood into the same, and another above the upper end of said lower part and spaced therefrom and leading from said hood, 80 a plurality of oppositely-arranged nozzles extending into said hood, means for supplying fluid-pressure to said nozzles, means for supplying material to be pulverized to said nozzles, whereby said fluid-pressure will force 85 said material from said nozzles, the material from one nozzle impacting against the material of its opposing nozzle, and being pulverized thereby, oppositely-arranged nozzles extending into said lower part of the draft-duct 90 and provided with similar means for pulverizing material as said first-mentioned nozzles, ducts leading from said hood to said lower nozzles, and an elevation formed in the floor of said hood between said first-mentioned nozzles and said ducts leading to the lower nozzles, the construction and arrangement being such that after the first impact 95 the pressure from the upper nozzles escapes through said draft-duct and carries with it 100 the pulverized material, and that part of the material not pulverized is drawn by said pressure over said elevation in the floor of said hopper and permitted to drop into the ducts leading to the lower nozzles, whereby 105 it is subjected to a second concussion and the material pulverized thereby is carried with the escaping pressure out said draft-duct, substantially as described.

4. The combination of a nozzle, a delivery 110 or discharge tip removably secured in the end of said nozzle; means of supplying material to be pulverized thereto, and a forcing-conduit delivering into said nozzle; said tip having a rifled bore for imparting rotation to the 115 material being forced through the same.

5. In a pulverizer, the combination of a pair of rifled nozzles adapted to have the material to be pulverized forced therethrough, 120 said nozzles being arranged opposite each other whereby the meeting of the streams of material is adapted to pulverize the same, of means for imparting an oppositely-rotating motion to said streams of material, consisting of similarly, internally rifled discharge-tips adapted to be applied to said nozzles, 125 substantially as described.

In testimony whereof I hereunto affix my signature in presence of two witnesses.

WM. F. McCLELLAN.
